(57) **CLAIM**

The ornamental design for an S-shaped wand, as shown and described.

DESCRIPTION

FIG. 1 is a perspective front view of an S-shaped wand;
FIG. 2 is a front elevation view of the S-shaped wand; the rear elevation view being a mirror image thereof;
FIG. 3 is a left side elevation view of the S-shaped wand;
FIG. 4 is a right side elevation view of the S-shaped wand;
FIG. 5 is a top plan view of the S-shaped wand; and,
FIG. 6 is a bottom plan view of the S-shaped wand.
